METHOD OF AND APPARATUS FOR
SENSITIZING PAPERSchuyler B. Davenport, Bound Brook, and Alfred
Savio, Dunellen, N. J.

Application March 3, 1934, Serial No. 713,930

4 Claims. (Cl. 91—10)

is invention relates to a method of and apparatus for sensitizing rotogravure carbon tissue.

It is an object of this invention to thoroughly sensitize the gelatine of rotogravure carbon tissue and in doing so, maintain the paper backing of the carbon tissue in a perfectly dry state during the entire operation in order that a sheet of carbon tissue sensitized through the teachings of this invention will dry in a very short time. This is a great advantage over the known methods where 5 the entire sheet of carbon tissue is submerged in a sensitized bath of bichromate solution and then squeegeed on a ferrotyp plate by hand. Uniformity of pressure throughout the surface of the tissue cannot be had by this method and the 10 sensitizing solution cannot be evenly distributed over the surface of the carbon tissue.

In those instances where carbon tissue constitutes the basic material for the printing of carbon prints from a positive film, whether it is 15 pictorial or design work, a plurality of carbon prints may be printed from one individual positive film and the result in the succeeding production will be uniformly perfect and, in this connection, an unusual number of such prints can be 20 made from one positive, as compared with known methods.

It has been found in practice with this invention that the timing of the sensitizing machine can be so arranged that the gelatine coating of 25 the carbon tissue becomes softened by the bichromate sensitizing solution so that the best results are attainable as the carbon tissue and the ferrotyp plate are conveyed through the machine, for as the bichromate solution is delivered 30 in a flowable state between the ferrotyp plate and the gelatine coating of the carbon tissue at a suitable temperature, it has a tendency to soften the gelatine coating of the carbon tissue in order 35 that it will adhere to the ferrotyp plate. The carbon tissue after the foregoing treatment is 40 permitted to dry in order that it may be removed from the ferrotyp plate and the gelatine coating of the carbon tissue which was of a dull finish before it was sensitized now has a highly glazed 45 surface finish, which latter condition is the ideal state for satisfactory results in its use, and since 50 the sensitized solution of each carbon tissue is a previously unused solution, the sensitized solution is clean and free of foreign elements or substances.

This is in contrast to the known methods where a great number of carbon sheets are subjected to the sensitizing solution contained in one tray. When so many sheets are subjected to the con-

tents of a single tray, certain particles of dirt are dislodged from the carbon tissue and find their way into the sensitizing solution and these foreign substances are to a greater or lesser extent imbedded in the gelatine coating of the carbon tissue, and furthermore a certain amount of the gelatine coating of the carbon tissue is dislodged from the carbon tissue and finds its way into the sensitizing solution, which affects the efficiency of the gelatine coating in the rotogravure art. 5

With the foregoing and other objects in view, 10 the invention consists in the details of construction and in the arrangement and combination of parts to be hereinafter more fully set forth and claimed.

In describing the invention in detail, reference 15 will be had to the accompanying drawings forming part of this application, wherein like characters denote corresponding parts in the several views, and in which—

Figure 1 illustrates a plan view of a machine 20 embodying the invention;

Figure 2 illustrates a view in elevation of one end thereof;

Figure 3 illustrates a view in elevation of the other end thereof; 25

Figure 4 illustrates a view in front elevation; and

Figure 5 illustrates an enlarged detail sectional view of fragments of the machine on approximately the line 5—5 of Figure 1 with those parts 30 of the machine beyond the section line omitted.

In these drawings 10 denotes a suitable frame in which a motor 11 is mounted, the said motor being preferably electrically driven and supplied with current through an appropriate conductor 35 12. A pinion 13 is in mesh with a gear wheel 14 on a shaft 15, the said shaft being journaled in the frame in any appropriate way and having on its end opposite the gear wheel 14 a pinion 16 meshing with a gear wheel 17 on a shaft 18. The shaft 18 also has a pinion 19 meshing with the gear wheel 20 on a shaft 21. By reason of the use of the gearing 17, 19 and 20, the r. p. m. of the shaft 21 is reduced as compared with the r. p. m. of the drive shaft and the drum or roller 22 on the 40 shaft is driven slowly. 45

Brackets 23 and 24 extend rearwardly from the frame and they are provided with a plurality of apertures such as 25 in which a pivot 26 applied to each bracket may be adjusted. An arm 27 having a slot 28 is applied to each pivot and a nut 29 threaded on a pivot serves to frictionally engage the arm and hold it in different positions of adjustment. The apertures 25 and slots 28 per-

mit a relatively wide range of adjustment of a table 30 whose outer end is supported by the arms, it being shown that each arm is connected to the table by a pivot 31. The inner end of the table 5 is supported on the periphery of the drum and receives the ferrotype plate and paper issuing from the machine as will presently appear.

The paper in its unsensitized state but having the gelatine coating is curled in a roll and as an 10 initial step in the operation, one end of the paper is attached to the front end of the plate by adhesive tape or some other appropriate means and the advanced end of the plate and paper are applied to the drum at the top thereof. A roller 32 engages the drum and the plate and paper are gripped therebetween by imparting to the drum an initial turning movement sufficient to start the 15 plate and paper between the drum and roller 32 and the remainder thereof rests in the trough 20 33 which is carried by suitably supported arms such as 34. Arms 35 and 36 are oscillatively mounted on pivots carried by the brackets 23 and 24 and a shaft 37 is journaled in the said arms 35 and 36. The roller 32 is mounted on the 25 shaft 37 and extensions 38 of the shaft constitute hand grasps by which the arms 35 and 36 are forced outwardly so that the periphery of the roller 32 is out of engagement with the drum for 30 since the roller is preferably rubber jacketed, the weight of the roller will tend to cause the periphery of the roller to become flat if it is allowed to rest on the drum when not in operation.

In order to hold the paper in place and to guide it between the drum and roller, standards 39 and 35 40 are attached to the arms 35 and 36 and they extend upwardly at the ends of the roller. Arms 41 and 42 are pivotally connected to the standards 39 and 40 respectively and rubber jacketed rollers 43 are journaled therein, the peripheries 40 of said rollers being in engagement with the periphery of the roller 32 or with paper interposed between the same, for when the machine is set for operation and the end of the paper has been attached to the end of the plate, the paper will lie 45 between the rollers 32 and 43 and extend rearwardly thereof.

In order to impart the initial motion to the drum for clamping the plate and paper between the drum and roller 32, the shaft 15 is provided 50 with a hand wheel 44 and by manually operating the hand wheel, the drum is turned and the plate and paper are given the initial movement so that they are clamped therebetween and will be fed through the machine when the motor operates to 55 drive the drum.

An electric switch 45 of any appropriate construction may be supplied at a convenient location as shown, but this may be changed to suit particular requirements.

60 A tank 46 for holding sensitizing solution is supported on the post or standard 47 in a plane above the machine so that the sensitizing solution will flow by gravity to the plate. In order to coat the plate with the sensitizing solution, the 65 tank is provided with a faucet 48 to which a hose 49 is connected, the said hose having a nozzle 50 so that by manipulating the nozzle, the sensitizing solution may be discharged on the plate preferably at the junction of the plate and paper as 70 the two are being brought into superimposed relation by the action of the drum and roller.

The foregoing method of sensitizing the paper may be repeated with each sheet, it being understood that the sheets are of certain well known 75 commercial size.

After a plate and the paper have been passed between the drum and the roller, the plate is forced out on the table 30 from whence it can be removed. The inclination of the table can be regulated by the adjustment of the arms 27 which 5 adjustment will compensate for the flowable character of the sensitizing solution and prevent its creeping on the paper, due to gravity.

Provision is made for moving the arms 41 and 42 so that the rubber jacketed rollers which they 10 carry can likewise be swung out of engagement with the roller 32, so that the said rollers will not become flat owing to their contact with the roller 32 when not in operation.

It will be observed that the arms 34 are slotted 15 and that they are adjustable on the pivots 34a and held in place by the nuts 34b.

The rod 51 connects the two standards 39 and 40 and projects beyond said standards to form stops 52 which are engaged by the arms 42 by 20 which the said arms are held elevated.

A holding rod 53 is carried by arms 54 pivoted on the standards 39 and 40, the said holding rod being movable into cooperative relation with the roller 32 to guide the paper as it is being moved 25 when the roller is rotated. The arms 54 may be held by springs such as 55 which are conventionally shown.

While the invention is directed to the coating 30 of what is known as "carbon tissue", in the description, this stock has been referred to as "carbon tissue" or "paper", by which terms the inventors wish to be understood as comprehending any basic material which is to receive a sensitizing 35 solution for use in the photo-engraving art.

We claim:

1. The method of sensitizing rotogravure carbon tissue consisting in attaching one end of a carbon tissue to an end of a ferrotype plate, interposing the superimposed plate and tissue between 40 rollers, driving the rollers to cause the rollers to move the plate and tissue therebetween, guiding the tissue into cooperative relation with the ferrotype plate, and depositing a sensitizing solution on the said plate substantially at the 45 location where the tissue and plate are contacted.

2. The method of sensitizing rotogravure carbon tissue consisting in holding one end of a carbon tissue in engagement with a ferrotype plate 50 between feeding rollers, holding the remainder of said tissue and the plate out of contact one with the other, applying a sensitizing solution in the space between the tissue and plate at their point of contact when moving, and in rotating the rollers to feed the plate and tissue therebetween. 55

3. In an apparatus for sensitizing rotogravure carbon tissue, a suitably driven roller, a roller mounted to coact with the first mentioned roller, suitably mounted rollers engaging the periphery 60 of the second mentioned roller operative to draw carbon tissue around the second mentioned roller and guide it to a location between the first and second mentioned rollers, a ferrotype plate engageable with the advanced end of the said carbon 65 tissue interposed between the first and second mentioned rollers, and means for depositing a sensitizing solution between the plate and tissue as it is transferred through the apparatus by the said rollers. 70

4. In an apparatus for sensitizing rotogravure carbon tissue, a suitably driven roller, a roller mounted to engage the periphery of the first mentioned roller and operative therewith, pivotally mounted arms in operative relation to the 75

second mentioned roller, the said arms having curved portions concentric with the second mentioned roller, rollers journaled in the said arms operative to engage the periphery of the second mentioned roller for guiding tissue therebetween, the said arms terminating in proximity to the coating portions of the first and second mentioned rollers, a ferotype plate having an end of

the carbon tissue attached to it interposed between the first and second mentioned rollers, and means for depositing a sensitizing solution at approximately the junction of the plate and tissue as they are brought into operative relation with each other.
